Primary Examiner — Jennifer Rivard(74) *Attorney, Agent, or Firm* — Myers Wolin, LLC(57) **CLAIM**

The ornamental design for a tweezer with scoop tips, as shown and described.

DESCRIPTION

FIG. 1 is a perspective view from one side of a tweezer with scoop tips showing our new design;

FIG. 2 is a perspective view from the opposite side thereof; FIG. 3 is a top plan view thereof, the bottom view being identical;

FIG. 4 is a front elevational view thereof, the rear view being identical;

FIG. 5 is a left side elevational view thereof;

FIG. 6 is a right side elevational view thereof; and,

FIG. 7 is a top plan view thereof showing the tweezer with scoops in a state of use.

The broken lines illustrate a portion of the tweezer with scoops and form no part of the claimed design.

1 Claim, 2 Drawing Sheets(56)
